UNITED STATES PATENT OFFICE

92,402

DESIGN FOR A COMBINED COUNTER AND DISPLAY STAND

Mathias Kaarstad, Fremont, Nebr.

Application March 17, 1934, Serial No. 51,084

Term of patent 3½ years

To all whom it may concern:

Be it known, that I, MATHIAS KAARSTAD, a citizen of the United States, residing at Fremont in the county of Dodge and State of Nebraska, have invented a new, original and ornamental Design for a Combined Counter and Display Stand of which the following is a specification, reference being had to the accompanying drawing forming part thereof.

In the drawing, Fig. 1 is a side view of the com-

bined counter and display stand showing my new design, and Fig. 2 is an end view of the same.

Fig. 3 is a plan view of the combined counter and display stand.

I claim:

The ornamental design for a combined counter and display stand, as shown.

In testimony whereof I affix my signature.

MATHIAS KAARSTAD.
